(57) **CLAIM**

The ornamental design for a socket for cold cathode fluorescent lamp, as shown and described.

DESCRIPTION

FIG. 1. is a front elevation view of a socket for the cold cathode fluorescent lamp showing my new design;

FIG. 2 is a back elevation view thereof;

FIG. 3 is a top plan view thereof;

FIG. 4 is a bottom plan view thereof;

FIG. 5 is a right side elevation view thereof, the left side being a mirror image thereof;

FIG. 6 is a top, front, and right side perspective view thereof;

FIG. 7 is a top, back, and left side perspective view thereof;

FIG. 8 is a cross-sectional view thereof, taken along 8—8 in FIG. 3;

FIG. 9 is a top plan view thereof, illustrating connection to a cold cathode fluorescent lamp and an adapter; and,

FIG. 10 is a top, front, and right side perspective view thereof, illustrating connection to a cold cathode fluorescent lamp and an adapter.

The broken line portion of the figure drawings is included to show unclaimed subject matter only and forms no part of the claimed design; and, the special dot-dash broken line defines the bounds of the claimed design and forms no part of the claimed design.
